TOILET SEAT COVER

Maurice Joyce, Port Washington, N. Y.

Application August 18, 1947, Serial No. 769,244

4 Claims. (Cl. 4—235)

1

This invention relates to a toilet seat assembly and more particularly to a toilet seat and a cover therefor, in the latter of which provision is made for the seating accommodation of infants and children.

It is an object of the invention to provide a toilet seat assembly having a cover attachment for the usual toilet seat in which is provided an opening of smaller size than that of the main seat. This opening in the cover is disposed at the front end thereof and a supplementary cover is provided for this opening which may be operated without difficulty by children themselves.

This invention presents an improvement over the toilet seat assembly disclosed in my Patent No. 1,990,869, February 12, 1935.

It is the object of the invention to provide an improved toilet seat assembly which is fabricated from molded materials to obtain a structure which is pleasing in appearance and easy to keep clean.

It is a further object of the present invention to provide a seat for a child in a molded cover for a toilet seat with a lid for said seat which is pivotally connected to the cover by a hinge arrangement which is completely embedded within the body of the molded cover. Aside from the fact that this supplemental lid requires no hardware, it functions effectively as a back rest for the child in one position, and as a smooth and finished closure for the opening in the toilet seat cover in the other position.

Other objects and purposes will appear from the detailed description of the invention following hereinafter, taken in conjunction with the accompanying drawing, wherein

Fig. 1 is a plan view of the arrangement in accordance with the present invention;

Fig. 2 is a side elevation of the toilet seat assembly for the accommodation of a child to be seated over the opening in the toilet seat cover;

Fig. 3 is an exploded view of the parts showing the hinge connections between the cover and the closing lid for the opening at the front thereof;

Fig. 4 is a sectional view along line 4—4 of Fig. 1; and

Fig. 5 is a vertical sectional view along line 5—5 of Fig. 1.

In the drawing, the main seat is designated by 1, and is adapted to rest upon the bowl of the toilet 2 through the intermediary of buffers 8. The main seat may be either of the type open at the front as shown in the drawing, or the well-known continuous oval type. In the rear structure 3 of the bowl are fixed brackets 4 which sup-

2

port the bolt 5. The main seat is hinged on the bolt 5 by sleeves 6, whereby the main seat may be moved between its raised and lowered positions.

The cover 7 for the main seat is formed of molded metal or plastic material of the type used in die casting operations of metals such as aluminum, magnesium or the like, or in injection molding processes of many well known organic plastics in wide commercial use today. A bore 20 is formed at the rear portion of the seat for the passage of the bolt 5 therethrough for pivotal mounting thereon, and buffers 8' on its underside cushion its downward movements against the toilet seat. As described in my earlier patent, an opening 21 is cut out of the front portion of the cover 7 and provides a comfortable seat for infants and children, permitting their feet to hang comfortably from the edge of the stool. The supplementary cover 9 is adapted to overlie the opening 21 and in the improved construction disclosed herein, this supplementary cover or lid 9 is pivotally connected to the cover 7 by a hinge arrangement which is completely concealed within the latter and which requires no hardware which might become unsightly in the course of time and which presents difficulties in keeping the same clean.

As shown in detail in Fig. 3, the rear part of lid 9 is formed with generally rectangular arms or projections 11 and 11' which engage in corresponding recesses 13 and 13', respectively, in the cover 7. Transverse pintles 12 extend through arm projection 11, while transverse pintles 12' extend through arm 11' and these pintles are adapted to be slid into the pairs of grooves 14 and 14', respectively, whereupon the pairs of splines 15 and 15' are inserted into the grooves in back of the pintles. Preferably each pair of pintles is formed of a cylindrical metal pin which becomes embedded in the respective arm in the course of the molding operation. When the cover is made of plastic material, a slight coating of solvent for the specific plastic of which the cover 7 and the splines are formed, serves to adhesively unite the splines into the grooves to provide a secure backing for the pintles, as shown in Fig. 5. Preferably, the ends 16 and 16' of the grooves 14 and 14', as well as the ends 17 and 17' of the splines 15 and 15', respectively, are formed of semi-cylindrical contour to provide a close seating of the cylindrical pintles 12 and 12'.

As shown in Fig. 4, a groove 19 in the rear face of the lid 9 permits clearance of the lid as the same is rotated from its position in the plane of

the cover 7 to a position transverse thereto as shown in dotted lines in Fig. 4, in which position the lid serves as a back rest for the child. In this position, the top surfaces of the arms 11 and 11' strike against the rearmost edges or bases 13a of the recesses 13 and 13' to act as a limiting stop for the lid in its open position as shown in Fig. 2, or in dotted lines in Fig. 4.

In the preferred embodiment of the invention, the seat 7 and supplemental lid 9 are formed of the same molded metal or plastic material, but if desired, each of these parts may be made of different materials or of different colored plastics, depending upon the ornamental and structural effects sought to be attained.

While I have described my invention as embodied in a specific form and as operating in a specific manner for purpose of illustration, it should be understood that I do not limit my invention thereto, since various modifications will suggest themselves to those skilled in the art without departing from the spirit of my invention, the scope of which is set forth in the annexed claims.

I claim:

1. A cover for a toilet seat formed of a molded material and provided with an opening therein for accommodating the seating of a child thereover, a supplemental lid for said cover opening also formed of molded material, and hinge means for pivotally connecting said lid to said cover comprising a pair of projections extending from the rear of said lid engaging a pair of corresponding recesses in said cover, pintles extending transversely from said projections and adapted to be fitted within grooves in the lateral walls of said recesses and backed with splines conforming to said grooves, whereby said pintles are completely embedded within said cover.

2. A cover for a toilet seat formed of a molded plastic material and provided with an opening therein for accommodating the seating of a child thereover, a supplemental lid of molded plastic material for said cover opening, and hinge means for pivotally mounting said lid comprising a pair

of projections extending from the rear of said lid engaging a pair of corresponding recesses in said cover, cylindrical pintles extending transversely from said projections and adapted to be fitted within grooves in the lateral walls of said recesses and backed with splines conforming to said grooves, whereby said pintles are completely embedded within said cover, the ends of said grooves and the inner ends of said pintles being of semi-cylindrical outline to provide close fitting seats for said pintles as the lid is moved from overlying position over said opening to a position transverse thereto for forming a back-rest for the child.

15 3. A device as set forth in claim 2 wherein the cylindrical pintles extending from each of said projections is formed of a unitary metallic pin embedded therein.

4. A cover for a toilet seat formed of a molded plastic material and provided with an opening therein for accommodating the seating of a child thereover, and a supplemental lid of molded plastic material for said cover opening, and hinge means for pivotally connecting said lid to said cover comprising a pair of projections extending from the rear of said lid engaging a pair of corresponding recesses in said cover, pintles extending transversely from said projections and adapted to be fitted within grooves in the lateral walls of said recesses and backed with splines conforming to said grooves, whereby said pintles are completely embedded within said cover, the top surfaces of said projections adapted to strike against the bases of the recesses in said cover in the raised position of said lid to provide a back-rest for the child.
